UNITED STATES PATENT OFFICE

2,647,177

DOUBLE BREAK SWITCH

Alfred J. Huck, St. Louis, Mo., assignor to Knapp-Monarch Company, St. Louis, Mo., a corporation of Delaware

Application February 25, 1950, Serial No. 146,259

2 Claims. (Cl. 200—5)

1

This invention relates to a double break switch and more particularly to a simple and novel modification which converts a single break switch into a double break switch.

A double break switch when used with electrical appliances is so arranged that one set of contacts are in one side of the supply line and the second pair of contacts are in the second side of the supply line. Where exposed electric elements are used, it is desirable to use double break switches because when the switch is "off" the exposed electric element is then completely disconnected from both sides of the electric circuit. It is particularly desirable to use double break switches on present day electrical appliances because Underwriters Laboratories have been very insistent that electrical appliances such as stoves and heaters which use exposed element coils, should incorporate double break switching so that a person will not obtain a shock by contacting the cold element coil, which with single break switching would still be connected to one side of the supply line.

In conventional double break switches, both sets of contacts break at the same time, and both sets are subject to deterioration from arcing. Furthermore, since double break switches generally have more parts than do single break switches, the double break switches are generally of larger size than are the single break switches.

There is also a substantial price differential between conventional double break switches and single break switches. For example, double break switches, at present, cost approximately 28¢ each in production quantities while single break switch, exemplified by the type described hereinbelow, cost approximately 11¢.

Thus, one of the objects of this invention is to provide a novel and simple modification for converting a single break switch into a double break switch.

Another object of this invention is to provide a novel double break switch in which only one set of contacts is subjected to deterioration from arcing.

Another object of this invention is to provide a double break switch in which one means is used to break one set of contacts, a second means is used to break the second set of contacts, and both means are actuated by a single control element.

A further object of this invention is to provide a double break switch in which one means is used to break one set of contacts, a second means is used to break the second set of contacts, and

2

in which the making and breaking of one set of contacts occur prior to or after the making and breaking of the second set of contacts.

Still another object of this invention is to provide a double break switch which is generally no larger in size than a simple single break switch.

A still further object of this invention is to provide a double break switch which is novel in construction and is relatively inexpensive to make.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which—

Figure 1 is a top plan view of a double break switch which incorporates in a single break switch the novel modification which converts the single break switch to a double break switch;

Figure 2 is an enlarged cross sectional view of the double break switch in Figure 1 taken substantially on line 2—2 of Figure 1, showing the switch in the "off" position;

Figure 3 is a view similar to Figure 2 showing the switch in the "on" position;

Figure 4 is a view of the double break switch taken substantially on line 4—4 of Figure 1;

Figure 5 is a bottom view of the double break switch taken on line 5—5 of Figure 4, showing diagrammatical the wiring arrangement of a circuit in which the switch is used; and

Figure 6 is a cross sectional view of the switch taken substantially on the line 6—6 of Figure 2.

Referring to the drawings, there is shown a reference character B to indicate generally a base and a T for a toggle lever. The base B is usually made of porcelain or the like and the toggle T is also made of an insulating material.

The base B is substantially cup-shaped and has formed integrally therein a plurality of internal mounting shoulders 11. These mounting shoulders 11 partially bound within the cup-shaped base B a pair of cavities, which will be referred to as upper cavity 12 and lower cavity 13. The lower cavity 13 is of smaller cross sectional area than the upper cavity 12. The single break switch comes equipped with a pair of terminals with internal and external contact points. The internal terminals 14 are strips of metal mounted vertically in the lower cavity 13 of the base and having edges adapted to be clasped by a contacting member. The internal terminals 14 are sup-

ported on shoulders 11 and are electrically connected to external terminal strips 15 by means of screws 16. The external terminal strips 15 are equipped with terminal screws 17.

Also mounted on support shoulders 11 is a support member S having a pair of flanges 18 extending upward within the upper cavity 12. The toggle lever T has mounted therein an insert 19 of substantially thick sheet metal. This insert 19 extends from toggle T into the upper cavity 12 of the base B. The insert 19 has a pair of lugs 20 extending therefrom which lugs 20 enter holes 21 in flanges 18 so as to position and support toggle T. The extended end of insert 19 is cut out to receive a bifurcated element 22 and to form therewith a toggle joint.

A U-shaped electrically conducting member 23 is pivotally supported by lugs 24 on arms 25, which arms 25 are part of flanges 18. The lugs 24 are integral with U-shaped member 23. The arms 25 are formed so that the lugs 24 are supported directly beneath the holes 21 in which are mounted the support pins 20 of toggle T.

The arms of the U-shaped member 23 have contact members 26 mounted thereon. These contact members consist of two pieces of thin sheet metal whose ends are bent outward slightly in a well known manner as shown in Figure 6. The ends of contact member 26 are adapted to spread as they clasp the internal terminals 14.

The U-shaped member 23 and the contact members 26 mounted thereon extend substantially within the lower cavity 13 of the cup-shaped base B.

A compressed spring 27 is positioned between the base of the U-shaped member 23 and the bifurcated element 22. The spring 27 acts to keep the U-shaped member 23 seated on support arms 25 and to keep bifurcated element 22 in engagement with insert 19. When the bifurcated element 22 is swung to an over center position the spring 27 forces the U-shaped member 23 to be pivoted on its lugs 24 to another position. There are two positions which the member 23 can assume, the first is bridging the gap between the terminals 14 by contact between contact members 26 and terminals 14 and the second is the non-conducting position when the gap between terminals 14 is re-established.

Figure 3 shows the switch in the first or "on" position and Figure 2 shows the switch in the second or "off" position.

In modifying this single break switch to a double break switch, I mount a pair of contact arms 28 and 30 on shoulders 11 within the upper cavity 12 of the cup-shaped base B. One contact arm 28 extends across the path of travel of a portion of the edge 29 of the toggle lever T. The other contact arm 30 is positioned out of the path of travel of toggle lever T as clearly shown in Figure 4. Silver contact points 31 and 31a are provided respectively on contact arms 28 and 30 because there is no wiping action between the contact arms and good electrical contact is desirable.

The contact arms 28 and 30 are normally urged toward each other so that good electrical contact is made. In the preferred form shown, contact arm 28 has sufficient resiliency to provide the urging force needed to make good contact with arm 30. When the toggle lever T is moved to the "off" position, the edge 29 of toggle T engages arm 28 and depresses that arm thus breaking the contact between contact points 31 and 31a. When the toggle T is moved to the "on" position

the arm 28 moves upwardly by reason of its resiliency and contact between points 31 and 31a is reestablished.

Contact arms 28 and 30 are secured to external terminal strips 32 by means of screws 33. The external terminal strips 32 are provided with terminal screws 34.

When the switch is moved from the "off" position to the "on" position, the toggle T is pivoted about pins 20. As toggle T pivots about pins 20 the edge 29 of the toggle T moves outwardly from upper cavity 12 and contact arm 28 moves upwardly until contact points 31 and 31a meet. This contact between points 31 and 31a is made before the toggle T passes through the center position. As the toggle T passes through the center position, the spring 27 moves the U-shaped member 23 so that contact members 26 engage internal terminals 14. Thus, any arcing that takes place will be between members 26 and internal terminals 14.

Similarly when the toggle T is moved from the "on" position to the "off" position, the contact between members 26 and terminals 14 will be broken before the edge 29 of the toggle moves sufficiently into the upper cavity 12 to deflect contact arm 28. Here, too, arcing will take place only between members 26 and terminals 14.

By reference to Figure 5 it will be noted that the terminal screws 17 are connected in one side of the circuit indicated by the wires a and b, while the terminal screws 34 are connected in the other side of the circuit indicated by the wires c and d. The load is indicated as a heating element 35 such as that found in an electric stove.

Thus, it can be seen that there has been provided a simple and novel mechanism whereby an inexpensive and relatively small single break switch may be modified into a more expensive double break switch without the necessity of increasing the size of the switch.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new and desire to secure by Letters Patent of the United States is:

1. In a switch comprising a cup-shaped base of insulating material having internal mounting shoulders forming substantially a lower cavity and an upper cavity therein, a manually actuated toggle member pivoted in said upper cavity on a pivot support mounted on a portion of the internal shoulders, a pair of spaced terminals mounted on said internal shoulders and extending downward into the lower cavity, said terminals adapted to be interposed in one side of an electric circuit, and engaging means operatively associated with said toggle member extending within said lower cavity and having portions thereof adapted to be selectively engaged and disengaged with said terminals; the improvement and modification of said switch comprising a pair of contactors mounted within said upper cavity upon said mounting shoulders and adapted to be interposed in the other side of said electric circuit, said contactors being resiliently urged into electrical conducting contact with each other, one of said contactors having a portion thereof positioned across the arc of swing of the pivoted toggle member, and said toggle member

adapted to engage said portion of said one contactor to separate said pair of contactors.

2. A switch as set forth in claim 1 wherein the means for engaging and disengaging said pair of spaced terminals extending within said lower cavity includes a spring pressed snap acting contactor, whereby the making and breaking of circuits in which said terminals and contactors are interposed is done in sequential order, said terminals being first disengaged and said contactors then being separated when the manually actuated toggle member is swung in one direction,

6
and the contactors first contacting and then the terminals being engaged when said toggle member is swung in the opposite direction.

ALFRED J. HUCK.
